UNITED STATES PATENT OFFICE

FRANK W. SALMAR, OF CHICAGO, ILLINOIS

CIGAR KNIFE

Application filed March 6, 1928. Serial No. 259,555.

My invention relates to the art of making cigars, and more particularly to the implements used on the hand-made product, and my main object is to produce a novel knife for the wrapper which is always in a handy position for use.

A further object of the invention is to so dispose the novel knife that it is always in the hand of the operator, and need not be laid down and picked up each time a wrapper is laid out for cutting.

Another object of the invention is to construct the novel knife to support itself on one of the fingers of the operator.

A final, but nevertheless important object of the invention is to design the novel implement in one simple structure, which is devoid of delicate or complicated parts, and may be produced at low cost.

With the above objects in view and any others that may suggest themselves in the specification and claim to follow, a better understanding of the invention may be gained by reference to the accompanying drawings, in which—

Figure 1 is a perspective view of the novel knife, showing the manner of its use;

Fig. 2 is an elevation of the knife;

Fig. 3 is a plan view; and

Fig. 4 is a perspective view of a modification.

In the art of making cigars by hand, the custom is to cut the wrappers to the proper shape by the use of a flat knife, comprising a blade of sheet metal of substantially elliptical form and with pointed ends, this knife being laid down on the table each time a wrapper is spread out and straightened in readiness to be cut or shaped. It may be imagined that the frequent act of depositing and again picking up the knife for each cutting operation when the work extends into a number of hours, becomes exceedingly tiresome to the operator and impairs his composure and efficiency. Furthermore, the conventional knife being a flat blade, it is not always readily picked up due to its closeness to the table surface, so that many moments' time are lost in the effort to pick up the knife with rapidity as the work progresses. Also,

the conventional knife is more or less wasteful, since it requires a long and graceful sweep to cut the wrapper with the proper curvature, and it is hardly possible under this condition to gauge the size of the wrapper to the proper and economical extent, so that with the sweep of the knife the wrapper is frequently cut considerably larger than is actually required, resulting in a waste of material. It has therefore been my intention to produce a knife which eliminates the above deficiencies and facilitates speed, comfort and efficiency in the cutting operation.

Referring specifically to the drawing, it will be noted that the knife 10 is composed of a sector-shaped blade, which is, of course, of a good grade of steel and sharpened along the curved edge. The upper or narrow part of the knife receives by riveting or welding a spring clip 11 whose ends are flared at 12 in an outward direction to render them smooth on the inside. These ends are also cut away from the bottom of the clip as indicated at 13, so as not to form an obstruction at that site.

When the novel knife is to be placed in use, the middle finger of the hand is inserted into the clip as indicated in Figure 1, the knife being on the inside of the hand. As the clip is of spring metal, it will hold to the finger and securely attach the knife thereto. The other fingers and the thumb are entirely free, and may be used with the fingers of the other hand to take up the next wrapper and spread the same into suitable shape to be cut. The knife is then drawn across the wrapper in the desired direction, the cut being almost entirely visible due to the small size of the knife, so that the latter may be drawn more accurately to the proper and economical size of the product, so that material is not wasted. It will be noted that the novel knife need not be removed or laid down for the purpose of taking up the next wrapper, as the balance of the fingers and the other hand may be used with facility, as explained; yet, the knife is instantly ready and firm when the next cut is to be made.

In the modification of Figure 4, a knife of greater length has been shown, although

the matter of length varies with the size of the wrapper and cut, and is therefore not an essential consideration; the knife performs the function in the same manner and its length may be varied without departing from its principle. However, in this instance the greater length of the knife permits the clip to be mounted on the ring finger, so that in case one desires to also roll the wrapper on the cigar after he has cut the same, he may with facility swing the knife past the middle and index fingers, or in the direction indicated by the arrow to locate the same in extended position on the outside of the hand. The knife thus employs but the ring finger to support it in this position, leaving the thumb and the balance of the fingers free to engage in the rolling operation. When the next wrapper is taken up for the cutting operation, it is an easy matter to swing the knife back to the inside of the hand, as shown in Figure 4, to the proper cutting position.

It will be seen that the novel cigar knife is a very handy article for the purpose intended. Being on the hand, it is always ready for use without any adjustment by the other hand to hold it in place. The time usually wasted in depositing and picking up the knife and the attention required for this purpose are eliminated in the present case, and the operator can acquire a greater speed in a short time, keep his composure due to the uniformity of the operations, observe economy in the cutting of the wrappers, and attain a marked degree of efficiency on general lines.

While I have illustrated and described the invention in the preferred form, it will be evident that the same is capable of many minor changes and refinements and it is my intention to claim such changes and refinements as coming within the spirit and scope of the appended claim.

45 I claim:—

A cigar knife comprising a blade having an arcuate cutting edge all points of said edge lying in the same plane, a spring finger engaging clip secured to the face of the blade and extending upwardly therefrom, said clip having an outwardly flared opening whereby said blade will transversely underlie several fingers of a hand to provide a bearing support therefor when said clip is engaged by one of the fingers of the hand.

In testimony whereof I affix my signature.

FRANK W. SALMAR.
